UNITED STATES PATENT OFFICE.

BENJAMIN C. CASSADY, OF PORTLAND, OREGON.

SCISSORS.

1,165,226.

Specification of Letters Patent. Patented Dec. 21, 1915.

Application filed March 15, 1915. Serial No. 14,463.

To all whom it may concern:

Be it known that I, BENJAMIN C. CASSADY, a citizen of the United States, residing at Portland, in the county of Multnomah, State of Oregon, have invented certain new and useful Improvements in Scissors; and I do hereby declare the following to be a full, clear, and exact description of the invention, such as will enable others skilled in the art to which it appertains to make and use the same.

This invention relates to improvements in scissors.

The principal object of the invention is to provide a pair of scissors which combine the features of the ordinary scissors and of the buttonhole scissors.

Another object is to provide a pair of scissors, the portions of which are adapted to be separated and one of them reversed, to accomplish the above-named result.

Other objects and advantages will be apparent from the following description when taken in connection with the accompanying drawing.

In the drawing: Figure 1 is a plan view of a pair of scissors made in accordance with my invention, the same being in position of the ordinary shears, Fig. 2 is a plan view showing one of the blades reversed, thus converting the scissors into buttonhole scissors, Fig. 3 is a section on the line 3—3 of Fig. 1, and Fig. 4 is a perspective view of the pivotal joint of the blades of the scissors.

Referring particularly to the accompanying drawing, 10 and 11 represent respectively a pair of scissors blades provided respectively with the finger hole handle portions 12 and 13. Intermediate the blade 11 and handle 12 of the scissors there is formed the vertical stud 14 having a transversely extending T-head 15 on the upper end. In the corresponding portion between the blade 10 and handle 12 of the other member there is formed a circular opening 16 centrally within which are the oppositely disposed approximately semi-circular flanges 17 extending inwardly toward each other in spaced relation and each formed with a curved recess 18 in the edge adjacent the other flange. The space between the flanges receives the key head 15 while the recesses 18 receive the stud 14 and permit the members of the scissors to be rotated whereby

the head 15 will lie on top of the flanges 55 and thus prevent the members from coming apart while at the same time permitting free pivotal movement therebetween.

Rigidly secured to the handle 13 is one end of a leaf spring 19, the other end of which bears on the other member of the scissors over the opening 16, thus frictionally holding the member against the first member. It will be noted that the head 15 is disposed flush with the surface of the 60 other member of the scissors so as to permit the spring to bear on that member of the shears. A thumb screw 20 is engaged through the spring 19 and through the shank of the handle 13 so as to increase or 65 decrease the tension of the spring. Carried by the handle 13 and extending in a direction toward the other handle 12 is a threaded stud 21 on which is mounted a threaded sleeve 22, this sleeve being adapted to be 70 adjusted on the stud so as to limit the closing movement of the handles.

On the back of the blade 10 is an extension 23, disposed intermediate the ends of the blade and having its outer edge beveled 80 to provide a shear blade as indicated at 24.

By opening the scissors to a comparatively wide position, the head 15 will be brought into registry with the space between the flanges 17 whereby the head will 85 freely move therethrough and permit the separation of the members of the scissors. The blade 10 can then be reversed to the position shown in Fig. 2, so that the edge 24 of the extension 23 can operate with the 90 blade 11 for the purpose of cutting buttonholes. It will be noted that the extension 23 is deeper at its inner end than at the outer end, the result being that the cutting edge inclines downwardly and outwardly 95 toward the point of the blade 10. This produces a perfect shearing action with the edge of the blade 11, and by adjusting the sleeve 22, the proportion of the edge 24 which will engage with the blade 11 for 100 cutting action can be increased or decreased thereby regulating the length of the cut of the blade 23 and consequently the length of the buttonhole.

Particular attention is called to the fact 105 that the blade 10 carries the ordinary scissors blade edge on one side and on the other side the short inclined cutting blade

whereby the said blade 10 can be reversed and can be used in ordinary cutting for cutting buttonholes.

What is claimed is:

- 5 A pair of scissors comprising cross pivoted members, each having a handle and a shear blade, one of said blades being provided with an outwardly extending shorter blade lying in the same plane therewith and
10 means for detachably pivoting the members

together whereby the said shear blade can be reversed to bring either of its cutting edges into co-operative engagement with the other blade.

In testimony whereof, I affix my signature, in the presence of two witnesses.

BENJAMIN C. CASSADY.
